CLAIM

The ornamental design for a CNC engraving machine with remote control set, as shown and described.

DESCRIPTION

FIG. 1 is a combination view of the first element and the second element of the first embodiment of a CNC engraving machine with remote control set showing our new design; FIG. 2 is a first perspective view of a first element of the first embodiment of a CNC engraving machine with remote control set thereof;

FIG. 3 is a second perspective view of the first element of the first embodiment thereof;

FIG. 4 is a third perspective view of the first element of the first embodiment thereof;

FIG. 5 is a front view of the first element of the first embodiment thereof;

FIG. 6 is a back view of the first element of the first embodiment thereof;

FIG. 7 is a left side view of the first element of the first embodiment thereof;

FIG. 8 is a right side view of the first element of the first embodiment thereof;

FIG. 9 is a top view of the first element of the first embodiment thereof;

FIG. 10 is a bottom view of the first element of the first embodiment thereof;

FIG. 11 is an enlarged view of the selected portion 11 in FIG. 2;

FIG. 12 is an enlarged view of the selected portion 12 in FIG. 2;

FIG. 13 is an enlarged view of the selected portion 13 in FIG. 2;

FIG. 14 is an enlarged view of the selected portion 14 in FIG. 4;

FIG. 15 is a first perspective view of a second element of the first embodiment of a CNC engraving machine with remote control set thereof;

FIG. 16 is a second perspective view of the second element of the first embodiment thereof;

FIG. 17 is a front view of the second element of the first embodiment thereof;

(Continued)

FIG. 18 is a back view of the second element of the first embodiment thereof;
 FIG. 19 is a left side view of the second element of the first embodiment thereof;
 FIG. 20 is a right side view of the second element of the first embodiment thereof;
 FIG. 21 is a top view of the second element of the first embodiment thereof;
 FIG. 22 is a bottom view of the second element of the first embodiment thereof;
 FIG. 23 is a combination view of the first element and the second element of the second embodiment of a CNC engraving machine with remote control set showing our new design;
 FIG. 24 is a first perspective view of a first element of the second embodiment of a CNC engraving machine with remote control set thereof;
 FIG. 25 is a second perspective view of the first element of the second embodiment thereof;
 FIG. 26 is a front view of the first element of the second embodiment thereof;
 FIG. 27 is a back view of the first element of the second embodiment thereof;
 FIG. 28 is a left side view of the first element of the second embodiment thereof;
 FIG. 29 is a right side view of the first element of the second embodiment thereof;
 FIG. 30 is a top view of the first element of the second embodiment thereof;
 FIG. 31 is a bottom view of the first element of the second embodiment thereof;
 FIG. 32 is an enlarged view of the selected portion 32 in FIG. 24;
 FIG. 33 is an enlarged view of the selected portion 33 in FIG. 24;
 FIG. 34 is an enlarged view of the selected portion 34 in FIG. 24;
 FIG. 35 is an enlarged view of the selected portion 35 in FIG. 24;
 FIG. 36 is a first perspective view of a second element of the second embodiment of a CNC engraving machine with remote control set thereof;
 FIG. 37 is a second perspective view of the second element of the second embodiment thereof;
 FIG. 38 is a front view of the second element of the second embodiment thereof;

FIG. 39 is a back view of the second element of the second embodiment thereof;
 FIG. 40 is a left side view of the second element of the second embodiment thereof;
 FIG. 41 is a right side view of the second element of the second embodiment thereof;
 FIG. 42 is a top view of the second element of the second embodiment thereof; and,
 FIG. 43 is a bottom view of the second element of the second embodiment thereof.
 The dash-dash broken lines shown in the drawings depict portions of the CNC engraving machine with remote control set that form no part of the claimed design. The dot-dash broken lines in FIGS. 2, 4, 11, 12, 13, 14, 24, 32, 33, 34 and 35 illustrate the periphery of the enlarged views of the CNC engraving machine with remote control set and form no part of the claimed design.
